CLAIM

The ornamental design for a bird house, as shown.

DESCRIPTION

FIG. 1 is a perspective view of a bird house showing my new design;

FIG. 2 is a side elevation view thereof;

FIG. 3 is a rear elevation view thereof;

FIG. 4 is a top plan view thereof; and,

FIG. 5 is a bottom plan view thereof.

The bird house is shown broken away in FIGS. 1-3 for convenience of illustration and to indicate indeterminate length.
